CLAIM

(21) **Appl. No.:** **29/641,413**

The ornamental design for a vehicle wheel, toy vehicle wheel, and/or replicas thereof, as shown and described.

(22) **Filed:** **Mar. 22, 2018**

DESCRIPTION

(30) **Foreign Application Priority Data**

Sep. 25, 2017 (DE) 40 2017 101 070

This application contains subject matter related to the following co-pending U.S. design patent applications:

Application Ser. No. 29/568,051, filed Jun. 15, 2016 and entitled Vehicle Wheel;

(51) **LOC (11) Cl.** **12-16**
(52) **U.S. Cl.**

Application Ser. No. 29/632,369, filed Jan. 8, 2018 and entitled Vehicle Wheel, Toy Vehicle Wheel, and/or Replicas Thereof;

(58) **Field of Classification Search**

Application Ser. No. 29/632,371, filed Jan. 8, 2018 and entitled Vehicle Wheel, Toy Vehicle Wheel, and/or Replicas Thereof; and

USPC D12/204-213
CPC B60B 7/00; B60B 7/02; B60B 7/04; B60B

7/01; B60B 7/06; B60B 3/02; B60B 3/04;
B60B 3/06; B60B 3/10; B60R 1/00;
B60R 1/08; B60R 1/10; B60R 1/12;
B60R 13/04

FIG. 1 is a perspective view of a vehicle wheel, toy vehicle wheel, and/or replicas thereof according to the design;

See application file for complete search history.

FIG. 2 is an additional perspective view thereof;

FIG. 3 is an additional perspective view thereof;

FIG. 4 is a front view thereof;

FIG. 5 is a rear view thereof in a lighter gray scale, representing environmental features that form no part of the claimed design; and,

FIG. 6 is a side view thereof.
